UNITED STATES PATENT OFFICE.

WILLIAM C. HUMMEL, OF HORNELL, NEW YORK.

ELECTRIC-LAMP SUPPORT.

1,181,011.

Specification of Letters Patent. Patented Apr. 25, 1916.

Application filed August 10, 1915. Serial No. 44,819.

To all whom it may concern.

Be it known that I, WILLIAM C. HUMMEL, a citizen of the United States, residing at Hornell, in the county of Steuben and State 5 of New York, have invented new and useful Improvements in Electric-Lamp Supports, of which the following is a specification.

My invention relates to electric lamp supports and more particularly to a support for 10 suspending a lamp from the ceiling.

The primary object of this invention is to provide a stationary tube and a sleeve movably mounted upon the tube and specifically supporting the lamp carrying tube acting 15 for the sleeve in an adjusted position whereby the lamp supporting tube may be adjusted within the path of an arc at right angles to the stationary tube.

Another object of my invention is to provide a device of this character which is efficient and durable in its construction and which may be manufactured at a nominal 20 cost.

With these objects in view, and others of 25 a similar nature which will appear as the invention is more fully understood, the invention consists in the features of construction and arrangement of parts hereinafter described and claimed, reference being had 30 to the accompanying drawings, in which:—

Figure 1 is a side elevation of my device showing the side view. Fig. 2 is a central vertical section of the same. Fig. 3 is a transverse section taken on line A—A of 35 Fig. 1. Fig. 4 is a vertical section of a modified form of Fig. 2. Fig. 5 is a detail view of the clamping ring.

Referring to the drawings in detail, 1 designates a canopy of the common form of 40 construction which is suitably attached to the ceiling of a room and is provided with an annular collar 2 surrounding the opening in the canopy, said collar being internally threaded to receive the threaded end of the 45 stationary tubular member 3. The tubular member 3 is vertically arranged within said collar and depends therefrom, the lower end of said tube having its adjacent side wall exteriorly threaded to receive a cap 4. This 50 cap is provided with a central opening which communicates with the interior of the tube 3.

Mounted upon the tube 3 and capable of vertical movement thereon is an annular sleeve 5, the outer side wall of which is provided 55 with a pair of laterally extending arms 6. These arms 6 are arranged in par-

allel spaced relation, each of which is provided with a transverse opening 7 adjacent the outer end, said openings 7 being arranged in registration with each other. 60 Supporting the sleeve 5 on the tube 3 is a clamping ring 5' which is of a substantially U-shaped configuration and has its upper edge flared outwardly to form a substantial support for the sleeve 5. 65

8 designates an annular collar which is provided with an upwardly extending ear 9, said ear being provided with a transverse opening therein. Passing through the openings in said arms is a pin 11 upon which the 70 ear is pivotally mounted, the ear being of such a width as to frictionally engage the confronting walls of the arms 6. The inner wall of said collar 8 is internally threaded to receive the threaded upper end of the 75 tubular member 12. The lower end of this tube 12 is externally threaded to receive a cap 13 which is provided with a vertically disposed opening adapted to pivotally receive the upper end of an electric lamp 80 socket 14. The walls of the opening in the cap 13 are provided with registering transverse openings which are adapted to receive the pins 15 which have the confronting extremities threaded within the lamp socket 85 14. The lamp socket 14 is provided with the usual internal threads which receive the lamp 16. Connected to the lamp 16 is the usual electric conductor cord 17 which extends upwardly through the socket 14 and 90 the tube 12 and out at the upper end of the tube and is then trained down through the lower end of the tube 3 and upwardly therethrough to the usual leads which are located within the wall. 95

From the foregoing construction it will be seen that when it is desired to vertically adjust the tube 12, upon the stationary tube 3, the clamping ring 5' having been removed, the operator is at liberty to vertically move the sleeve upon the tube. Having placed the sleeve in its desired position, the clamping ring is then inserted upon the tube beneath the sleeve, thereby supporting said sleeve and holding the lamp carrying member in the corresponding position. The opposite ends of the tube 3 being provided with projections formed by the collars 2 and the cap 4, the sleeve 5 is locked upon the tube and any accidental displacement of 105 the same is prevented. If it is desired to elevate the lamp 16 upon the sleeve 5, the 110

tube 12 may be moved outwardly and upwardly owing to the fact that the upper end of the tube is pivotally mounted within the parallel arms 6. The fact that the ear 9 frictionally engages the side walls of the arms, permits the tube 12 to be rigidly held in any position upon its support. The lamp socket 14 being pivotally mounted within the cap 13 permits the lamp to be swung to any angle thereby obtaining the maximum amount of light from the lamp.

In Fig. 4 I have shown a modified form of the tube 12 comprising the two telescopic members 17 and 18 respectively, 17 being provided with the ear 9 and pivotally mounted between the arms 6, the slideable portion 18 being provided with the cap 13 which pivotally receives the socket 14. It will be seen from this construction that the member 18 being slideably mounted within the member 17 permits the tube to be lengthened or shortened and the corresponding adjustment of the lamp 16.

What is claimed is:—

1. A lamp support comprising a tube, means for suspending said tube, a sleeve movable on said tube, a clamping ring secured to said tube and supporting said sleeve, parallel spaced arms formed on said sleeve and extending laterally therefrom, a lamp supporting tube, an ear formed on one end of said tube and pivotally mounted between said arms, the sides of said ears fric-

tionally engaging the inner faces of the arms.

2. A lamp support comprising a tube, means for suspending said tube, a sleeve movable on said tube, a clamping ring mounted on said tube and supporting said sleeve, parallel spaced arms formed on said sleeve and extending laterally therefrom, a second tube, an ear formed on one end of said tube and pivotally mounted between said arms, a cap formed on the lower end of said last mentioned tube and having an opening formed therein, a lamp socket pivotally secured to the inner wall of said opening, the outer wall of said socket adapted to frictionally engage the inner walls of the opening of said cap.

3. A lamp support comprising a tube, means for suspending said tube, a sleeve movably mounted on said tube, a clamping ring mounted on said tube and supporting said sleeve, parallel spaced arms formed on said sleeve and extending laterally therefrom, a second tube pivotally mounted between said arms, and a lamp supporting tube telescopically mounted within the last mentioned tube.

In testimony whereof I affix my signature in presence of two witnesses.

WILLIAM C. HUMMEL.
